UNITED STATES PATENT OFFICE

166,878

TEXTILE FABRIC

Henry Rose, New York, N. Y.

Application January 9, 1952, Serial No. 17,972

Term of patent 3½ years

(Cl. D92—1)

To all whom it may concern:

Be it known that I, Henry Rose, a citizen of United States of America, and a resident of New York, in the county of New York, and State of New York, have invented a new, original, and ornamental Design for a Textile Fabric, of which the following is a specification, reference being had to the accompanying drawing, forming part thereof.

In the drawing:

The figure is a plan view of the textile fabric, showing my new design.

A design unit is outlined by broken lines and is repeated as indicated.

I claim:

The ornamental design for a textile fabric, substantially as shown and described.

HENRY ROSE.
